FIG. 1

1

3,104,635

SHUTTLE-MOVING MECHANISM FOR SCHIFFLI EMBROIDERY APPARATUS
Theodore Bohus, 7024 Durham Ave., North Bergen, N.J.
Filed June 29, 1962, Ser. No. 206,223
4 Claims. (Cl. 112—95)

The present invention relates to an improvement in Schiffli embroidering machines of the type having a great number of simultaneously-movable embroidering needles arranged in horizontal rows, with each needle having a cooperating, diagonally vertically movable shuttle. More specifically, the present invention is directed to an improvement in the mechanism for moving the shuttle of such apparatus.

In apparatus of the character described, the shuttle for each needle is guided on a shuttle-box which is mounted on a horizontally-fixed shuttle box-supporting bar and is provided with a shuttle-supporting face that is disposed in a plane that is transverse to the shuttle box-supporting surface of the bar and is at a slight angle to a plane perpendicular to that surface. The shuttles are each reciprocated on their sloping supporting surface in an upward direction by a drive pin engaging its bottom and held in place on a horizontally-disposed bar that is reciprocated along an angle parallel to the shuttle-supporting faces. The apparatus is also provided with means that will assure the downward or return movement of the shuttle to initial position, by its own weight, and that such return will not be interrupted by binding against the shuttle-supporting or adjacent surfaces.

In the Schiffli embroidering machines of the prior art, the means for assuring the return of the shuttle to its initial or lowermost position have been another set of bars or fingers supported on the shuttle-moving bar in vertically-spaced relation and in position to have an end thereof engage the upper end of a shuttle whose downward movement has been interrupted, to push such shuttle down to initial position. Normally, such shuttle-returning fingers are arranged to have their ends disposed in slightly spaced relation to the upper ends of their respective shuttles and to contact a shuttle only in the event its downward movement is in some way interrupted.

In apparatus of the prior art, as described above, the shuttles are generally held loosely in position and frequently, due to the vibration of the apparatus or to the sharp movement of the shuttle-moving means, or for other reasons, they move sharply away from and toward their supporting surfaces, as a result of which missed stitches frequently occur and also considerable damage and abrasion of the shuttle-supporting surface or the shuttle-box is caused. These results bring about inferior work and the need for shuttle-box replacement that involves not only shuttle-box and labor costs, but also the cost of machine layoff time.

It is the object of the present invention to provide improved means on a shuttle-moving bar that will positively return a shuttle from its upward to its initial, lower position, and at the same time prevent it from bouncing away from its supporting surface on a shuttle-box, and thereby prevent missed stitches as well as undue wear on and damage to its supporting surface.

It is another object of the present invention to provide improved means for returning a shuttle to its initial, lowermost position, which are certain and positive in their operation.

It is a further object of the present invention to provide improved means for returning a shuttle to its initial, lowermost position which are of relatively simple construction and relatively easy and economical to install, on new as well as existing apparatus.

The foregoing and other objects and advantages of

2

the shuttle-returning means for Schiffli-embroidering apparatus of the character described will become more readily apparent to those skilled in the art from the embodiment thereof shown in the accompanying drawings and from the description following. It is to be understood, however, that such embodiment is shown by way of illustration only, to make the principles and practice of the invention more readily comprehensible, and without any intent of limiting the invention to the specific details therein shown.

10 In the drawings:

FIG. 1 is a fragmentary, elevational view of the shuttle-supporting and moving mechanism of a Schiffli embroidery machine embodying the present invention, partly broken away to show structural details; and

15 FIG. 2 is an enlarged, sectional and partly elevational view of the same, taken on line 2—2 of FIG. 1.

Referring now in greater detail to the embodiment of the invention illustrated in the accompanying drawings, 20 there is shown a more or less standard shuttle-supporting bar, 10, which is fixed in position on the apparatus in any well known manner not thought necessary to be illustrated, on which are supported a plurality of standard shuttle-boxes, generally designated as 12, which may each 25 be secured in place on the bar 10, as by set screws 14, passing through the bar 10, and engaging in the base 16 of the shuttle-box.

The shuttle-box 10 each comprise an upwardly-extending block which is tilted at an angle, as about 15°, 30 to the vertical, and has, on one side, a smooth supporting and gliding surface 18 for the flat face of a shuttle 20. Each shuttle-box 10 is also provided with a conventional needle-groove 22 opening into the shuttle-supporting face 18 thereof.

35 The means for reciprocating a shuttle 20 on a supporting face 18 comprises a frame, generally designated as 24, which may be of any standard type, or, as illustrated, comprise a pair of substantially flat, vertically spaced, interconnected horizontal bars, including a lower 40 horizontal bar 26 and an upper horizontal bar 28, which are spaced so as to provide a distance equal approximately the height of a shuttle 20 between their remote surfaces. The frame 24 is operatively connected to the operating mechanism of the apparatus for movement, as 45 a whole, along an angle parallel to the plane of the shuttle-supporting surface, by means of a rod 30 secured to the frame 24, as at 32, which rod is guided in diagonal guiding means 34 secured to the shuttle-box-supporting bar 16. The means for moving each shuttle 50 in an upward direction may be of any conventional type and may comprise a shuttle drive pin 36 held against the underside of bar 26 of frame 24, as by means of the plate 38, which is secured to the underside of bar 26, as by the screw 40, passing through the plate and 55 engaged in the bar 26. Each pin 36 is arranged to engage the bottom or thicker end of a shuttle 20 to move it upward upon upward movement of the frame 24. The return movement of each shuttle is primarily effected by gravity. However, to assure its return movement 60 against interruption, as by binding against the sides of the shuttle-box, a return bar or finger 42 is provided, supported on the top bar 28 of frame 24 and, preferably adjustably, held in place in any conventional manner, as by a curved spring 44, which engages by an edge 65 a finger 42, and is, in turn, held in place by a screw 46 passing therethrough and engaged in the upper bar 28 of the frame 24. The inner end of the shuttle-returning finger overlies the top or thin end of a shuttle 20, in the conventional manner.

To maintain the shuttle 20 against the supporting surface 18 of a shuttle-box 12, as well as return it to lowermost position, I secure to the inner end of the associated

return finger 40, which is generally spaced slightly from the top end of the shuttle, a dependent resilient member, as in the form of a leaf spring 48, the upper end of which is secured, as by soldering or welding, to the end portion of the finger 40 overlying the associated shuttle. The spring 48 is so positioned and so curved and shaped that its dependent end will press slightly, resiliently, against the curved face of the shuttle 20 at approximately the center of its curvature, at a slight distance from the top end of the shuttle. The dependent end portion of the spring 48 is preferably curvedly offset, as at 50, so that such end portion lies flatly against the sloping shuttle surface at point of contact.

By this construction and arrangement, the shuttle is at all times in contact with its elevating pins 36 and at all times in resilient contact with its returning finger 40, so that the shuttle will not jump either upwardly on its upper movement or bounce away from its supporting surface either on its upward or downward movement, but will always remain in contact with its supporting surface, under slight pressure, and will be prevented from missing any stitches or abrading the supporting surfaces.

This completes the description of the shuttle-moving mechanism for Schiffli embroidery apparatus of the present invention. It will be readily apparent that such mechanism, though of simple character and economical to install, will be highly effective for its intended purposes of assuring the lowering of the shuttles on the shuttle-boxes and at the same time eliminating the bouncing of the shuttles, to thereby eliminate missed stitches and reduce resulting wear and tear on the shuttle-boxes and the shuttles, to thereby effect economies in operation and maintenance of the apparatus.

It will also be apparent that numerous variations and modifications in the shuttle-moving mechanism of the present invention may be made by anyone skilled in the art, in accordance with the principles of the invention hereinabove set forth, and without the exercise of any

inventive ingenuity. I desire, therefore, to be protected for any and all such variations and modifications that may be made within the spirit of the invention and scope of the claims hereto appended.

I claim:

1. In a Schiffli embroidering machine having means supporting a shuttle for diagonally vertical reciprocating movement and means moving a shuttle on said supporting means including a shuttle driving pin engaging the bottom of a shuttle and means moving said driving pin in a diagonally vertical direction, shuttle returning means comprising an element movable with said driving pin and extending over the top of a shuttle supported on said supporting means and vertically spaced from said shuttle top and a resilient member connected to said element engaging the outer face of said shuttle adjacent its top end.

2. The shuttle returning means of claim 1, wherein said element comprises a rod and said resilient member engaging said shuttle comprises a spring element dependently secured to said rod.

3. The shuttle returning means of claim 1, wherein said element comprises a rod and said resilient member engaging said shuttle comprises a leaf spring secured to said rod by one end thereof with the other end thereof engaging against the outer surface of said shuttle at substantially the center of the circumferential curvature thereof.

4. The shuttle returning means of claim 3, wherein said leaf spring is formed with an offset free end shaped to lie against the surface of said shuttle at point of contact.
